UNITED STATES PATENT OFFICE

RICHARD CRETER, OF NEW YORK, N. Y.

ELECTRIC RAILROAD SYSTEM

Application filed June 6, 1928. Serial No. 283,263.

This invention relates to electric railroad systems, and more particularly to a safety system for electric railroads for the prevention of collisions.

5 An object of the invention is to provide an electric railroad with a safety system which is capable of automatically cutting off the electric energy in the third rail or equivalent means feeding a posterior train and thus 15 stopping the said train and preventing it from colliding with an anterior train.

Another object is to incorporate a signal in my new system which will warn the operator of the train of the traffic conditions on 20 the track or associated tracks ahead of him.

A further object is the provision of an auxiliary device in the air brake system which will automatically apply the air brakes when the train has entered a dead zone.

25 Other objects and advantages of the invention will become apparent from the following description taken in conjunction with the accompanying drawings, in which:

Fig. 1 depicts somewhat diagrammatically 28 a miniature railroad system having my invention embodied therein;

Fig. 2 shows in a diagrammatic manner 33 an electric railroad system embodying my invention which has a main and a local spur track;

Figs. 3, 4, and 5 are views similar to Fig. 2 except that they show modified systems;

Fig. 6 illustrates a signal device for use 38 in the system depicted in Fig. 1;

Fig. 7 is a fragmentary detail view, on an 43 enlarged scale, of the upper part of the signal device shown in Fig. 6;

Fig. 8 represents the signal device used 48 in the electric railroad system illustrated in Fig. 5; and

Fig. 9 illustrates an auxiliary device for 53 automatically releasing air to the air brakes when the train enters a dead zone.

Generally speaking, the present invention 58 contemplates incorporating an automatic power cut-off system for preventing collisions in an electric railroad at critical portions thereof and in such a manner that a posterior train approaching an anterior train has the 63 electric energy therefor automatically cut off

when the posterior train attempts to proceed into the same block or the same sphere in which the anterior train is located. In addition to cutting off the electric energy from the third rail or supply wire feeding the posterior 58 train, my invention provides a signal device which is positioned at critical points so as to be in full view of the operator of the posterior train and to indicate whether the block ahead of him is clear or is obstructed with 60 traffic. In case the operator does not apply the air brakes on the train my auxiliary device which is incorporated in the power circuit and the air brake system automatically causes the application of the air brakes to 65 stop the train. By including the aforesaid features of my invention in an electric railway system collisions of a posterior train with an anterior train is absolutely prevented and all possibility of such collisions is eliminated. 70

Reference is now to be had to Fig. 1 which depicts an embodiment of my invention in the form of a miniature railroad system commonly used as a play toy. The reference character A designates an anterior train which is running on an outside loop O of a closed railway track C. On the inside loop I of the railway system a posterior train P is operating on electric energy derived from a common 75 source F, such as an electric generator of any well known type. The electric energy is fed to the trains by means of a third rail T, which is illustrated as being between the two railroad tracks.

Located at a critical or control point in the railroad system, which is herein shown as at the beginning of the curved portions of the tracks prior to their converging into a common return track R, is an automatic 80 power cut-off system designated generally by the letter S. This automatic cut off system, broadly stated, consists of an electro-magnet circuit M which is connected to a live section L of track and an armature circuit K which 85 is connected to a dead section D of track which is capable of being rendered dead, i. e. of being de-energized when a train is in the live section L which is ahead of the dead section D or is in conflicting relation therewith. The 90 95 100

electro-magnet circuit M may be composed of a magnet 1 (or solenoid or equivalent device) which is connected in series with one track and the third rail by means of conductor 2 leading to the outside track and conductor 3 leading to the third rail via resistance 4. By inserting this resistance in the magnet circuit the intensity of the electric current can be reduced to any desired value.

10 Shunted across the magnet circuit is an electric circuit containing a signal device. This device is herein illustrated as an electric light 5 which is fed with electricity by conductors 6 and 7 from joints 8 and 9 respectively in 15 the magnet circuit. The electric light may be positioned in any appropriate position with respect to the outside loop O but is preferably located between the front of the anterior train and the point where the magnet 20 circuit is connected to the third rail and track so that the signal is visible to the anterior train before it proceeds into the curve Z which leads into the return track R.

Associated with the inside loop I is the 25 armature circuit K or counterpart of the electro-magnet system described hereinabove. In the armature circuit an armature 10 is positioned adjacent to and in cooperative association with the end of magnet 1 and is adapted 30 to swing about pivot 11 when the magnet is energized and de-energized. The armature 10 is normally held out of contact with the end of the magnet by a spring 12 which holds the armature against contact 13 or some other 35 appropriate switching apparatus capable of operating on the voltage utilized in the third rail, and thus establishes an electrical connection between conductors 14 and 15. These conductors are connected to portions of the 40 third rail which are separated by an insulating block 16 so that the third rail circuit is only completed when the armature 10 engages contact 13. By inserting another insulating body 17 in the third rail, a section 45 of track extending between blocks 16 and 17 herein known as the dead section, can be energized and de-energized according to whether the armature 10 is in engagement with contact 13 or out of engagement with it.

50 A signal device depicted herein as an electric light 20 which is energized by electricity flowing through conductors 21 and 22 leading to a track of the inside loop and the line 14 and third rail respectively. Light 20 illuminates two signals consisting of a right hand signal emitting red light for the anterior train and a left hand signal emitting green light for the posterior train. A description 55 of the aforesaid signal will be given hereinafter in greater detail.

The operation of the aforesaid electric railroad system embodying my invention is obvious to those skilled in the art. When the anterior train enters the live section L 60 of track by passing over insulating block 19

interposed in one of the tracks of the outside loop, the magnet circuit M is energized, i. e. a circuit is formed from the third rail through the train to the aforesaid track and through conductor 2, magnet 1 and back 70 through resistance 4 and conductor 3 to the third rail. The electrical energy which passes through the electro-magnet circuit energizes magnet 1 and attracts the armature 10 against the end thereof, thus withdrawing the armature from contact 13 and opening or breaking the circuit between conductors 14 and 15 which are associated with parts of the third rail on each side of insulator 16. Due to the passage of current through the 80 electro-magnet system, light 5 is illuminated so that the right hand green light indicates to the anterior train that it is safe to proceed. The same light illuminates a left hand red signal light, which is adapted to warn the 85 posterior train it is dangerous to proceed. In addition to warning the posterior train of the danger ahead of it, armature 10 breaks the third rail connection so that no electrical 90 energy flows through conductor 15, armature 10 and return conductor 14, connected to the portion of the third rail which is isolated by insulating blocks 16 and 17. The dead section of the track coincident with the dead or de-energized third rail section is of such 95 a distance that the train even though proceeding under substantial velocity will be slowed down and practically come to a stop by the time it reaches the automatic cut-off system S. Of course, if the brakes are applied to 100 the train as soon as the train enters the dead section, then the train will be stopped within a very short range. Under these conditions it is safe for the anterior train to proceed and pass the automatic power cut-off system S 105 and to continue its journey.

After the anterior train has left the section of track defined by insulating blocks 18 and 19, the circuit feeding the magnet 1 will be broken and consequently the magnet will 110 be de-energized. As soon as the magnet is de-energized, spring 12 pulls armature 10 away from the end of the magnet and brings it into engagement with contact 13, thus completing the circuit between conductor 15 and return conductor 14. The section of third rail between insulating blocks 16 and 17 is thus energized again and electricity 115 flows to electric light 20. This light illuminates a left-hand green signal which indicates to the posterior train that it is safe to proceed, and which also warns any train on the outside loop that it is dangerous to proceed.

It will be noted that by the incorporation 120 of my improved system in an electric railroad, it is practically impossible for a posterior train to run into and collide with an anterior train because I provide in addition to signals, an automatic power cut-off sys- 125

tem which automatically shuts off the power feeding the posterior train.

Although I have described my invention in connection with a miniature train system which is intended to be operated as a toy, it will be observed that the same principles can be embodied in a regular railroad system and accomplish the same ends.

In Fig. 2 I have illustrated a railroad system having a main line which is fed by a spur local road. The main line is intended for through traffic or express traffic, whereas the local line is intended for trains which stop at a great many intermediate stations, one of which I have illustrated in the drawings.

The numeral 30 designates the main line and the numeral 31 the local line. Just ahead of the junction 32 of the main and local tracks I provide my automatic power cut-off system S. The cut-off system is similar in structure to the system described hereinabove and consists, structurally speaking, of an electro-magnet circuit M associated with a live section of track L and an armature circuit K operatively connected to a dead section D of track.

In this example the live section L is illustrated as a portion of track on the main line defined by insulators 18 and 19 incorporated in one of the tracks 35 and the dead section D is illustrated as extending between insulators 16 and 17 interposed in the third rail T' of the local track. The magnet circuit is arranged and connected to the express track in the same manner as the magnet circuit is arranged and connected to the outer loop O of track in Fig. 1, and the armature circuit is arranged and connected to the local track L-T in the same manner as the armature circuit is arranged and connected to the inner loop I of track in Fig. 1. In view of the fact that the arrangements and connections are the same as in the example described under Fig. 1, it will not be necessary to repeat the same description at this point.

When the express train passes into the live section L defined by insulators 18 and 19, the express train completes the circuit leading to the magnet. In this magnet circuit current flows from the third rail T through the train to track 35 and into conductor 2 and magnet 1. By selecting a resistance 4 of proper size any desired amount of current can be permitted to flow to the electric magnet 1. When electric current energizes the electro-magnet, armature 10 is attracted to the end of the magnet and is withdrawn out of engagement with the contact 13. When this occurs the circuit constituted by conductor 14, armature 10 and conductor 15 is broken so that the dead section D of third rail T' associated with the local track between insulating blocks 16 and 17 is de-energized or rendered dead. A local train,

therefore, which is in this section of track will not receive any power and consequently will not be able to operate or proceed. This means that even though the operator of the train on the local track disregards the red signal caused by the illumination of light 5, he will not be able to proceed because there will be no electrical power in the third rail between the insulating blocks 16 and 17. It is therefore perfectly safe for the express train to proceed right through on the main line.

After the express train has passed beyond insulating block 18 the electro-magnet in the automatic power cut-off system is again de-energized and the armature 10 is pulled by the spring 12 against contact 13. When this occurs electric light 20 is illuminated so that it causes a right hand signal to emit a green light and a left hand signal to emit a red light. The local train can, upon the illumination of light 20, then proceed because the section of the third rail T' is again energized by electricity flowing from conductor 14, armature 10 and conductor 15.

A one track railroad system is shown in Fig. 3 to exemplify an embodiment of my invention in this type of railroad. In order to avoid rear end collisions in a one track system, I incorporate my system in the railroad at critical points thereof. Thus, for example, I position my automatic power cut-off system S at point X on the track a considerable distance ahead of the railroad station. This distance, of course, will vary with the particular circumstances and conditions but one skilled in the art will be able to select a distance which will be appropriate for the protection of the operation of an anterior train A so that there will be no possibility of a collision with a posterior train P.

The automatic power cut-off system has an electro-magnet circuit M connected to a live section L of track 40 and has armature circuit K connected to a dead section D of track in the same manner as explained hereinabove.

The armature circuit K is connected to a dead section D of track at a point 43 which is isolated from the third rail by an insulating block 18.

Associated with the insulating block 19 is a cooperating insulating block 18 at an antecedent point in the third rail T'. This section, herein known as the dead section D, is adapted to be cut-off from the electric power flowing in the main line T, T'. Ordinarily I prefer to have the section of track defined by blocks 18 and 19 of such a distance that a train proceeding at a considerable velocity will slow down and practically come to a dead stop even though the brakes have not been applied by the operator of the train upon coming into the aforesaid section of track.

In the section of the track associated

with automatic power cut-off system S, I interpose insulating blocks 16 and 17 in one rail so as to define a live section L of track within which my automatic cut-off system will become operative. For example, when the anterior train A gets into the section defined by blocks 16 and 17, the electro-magnet circuit is completed and energy flows from the third rail through the circuit so as to 10 energize magnet 1. The magnet thus being energized, attracts armature 10, as explained hereinabove, and thus breaks the circuit constituted by conductors 14 and 15 and their associated third rail sections. Energy no longer flows from the third rail T, T' through conductors 15 and 14 to the dead section D of the third rail between blocks 18 and 19. This latter section is thus rendered dead or inactive so that no power can be obtained by the posterior train P upon entering this section of the track. The posterior train therefore, is automatically slowed down and brought to a stop by friction, and, thus, the possibility of any collision between the 20 posterior train and the rear of the anterior train is absolutely eliminated.

After the anterior train A passes beyond the insulating block 16 the electro-magnet 1 is de-energized and the armature 10 is 30 pulled into contact by spring 12 with contact 13. Thus the third rail T, T' is again connected to the third rail between blocks 18 and 19 by conductors 15, 10 and 14. When this latter circuit is completed electric 35 light 20 which is connected to conductor 15 by an electric connection 21 and to the rail by conductor 22, is illuminated and signals to the operator of the posterior train P that he may proceed with safety.

40 In some of the figures of the drawings I have shown the conductors 14 and 15 of the armature circuit, which connect a portion of the third rail located in the dead section to the rest of the third rail as being quite long. 45 In actual practice, however, the armature and magnet would be placed in close relation to insulator block 18 so that the heavy current-carrying conductors 14 and 15 would be relatively short and the light conductors 50 2 and 3 leading to the electro-magnet would be relatively long. By arranging the parts in this manner a more economical installation may be made than when a large amount of expensive heavy copper conductors are used.

55 The principles of my invention are incorporated in another single track system depicted in Fig. 4. In this figure a station is shown which has an anterior train A in front of it. A posterior train P runs on the same 60 track with the anterior train, but by the incorporation of my automatic power cut-off system in this system in the same manner as described under Fig. 3, all possibility of rear end collisions between the anterior train A and the posterior train P is absolutely

eliminated. In view of the fact that the arrangement of elements and structural features is the same as that system illustrated in Fig. 3 and described hereinabove, it will not be necessary to repeat the said description 70 at this point.

The signal device which I prefer to use in conjunction with the railroad systems described hereinabove is illustrated in Figs. 6 and 7. Signal lights 5 and 20 are mounted 75 on a support 100 which is secured within a metallic casing 101 of any appropriate type or design. In these figures light 5 is shown as being mounted on the lower side and light 20 on the upper side of partition 112, although it is to be understood that in some cases the positions of these lights will be reversed to suit the requirements of the particular railroad system. Casing 101 is provided with well known ventilating means such as 80 holes 114 and is secured on the top of a pedestal 102 which may be set upon a concrete foundation in the ground or upon any other suitable structure. At the base 103 of the pedestal binding posts 104 and 105 are provided for making connections with the signal conductors connected to lights 5 and 20 respectively. In the enlarged fragmentary 85 sectional view shown in Fig. 7 conductors 106 extending from the binding posts 104 to signal light 5 and conductors 107 extending from binding posts 105 to signal light 20 may be clearly seen.

The face of the casing has four glass windows 108, 109, 110, and 111, windows 108 and 111 being green and windows 109 and 110 being red. Within the casing partition 112 divides the casing into an upper portion containing light 20 and a lower portion containing light 5. When light 20 is illuminated in the upper portion a green light is emitted by window 108 and a red light by window 109, whereas when light 5 is illuminated in the lower portion, a red light is emitted by window 110 and a green light by window 111. In practice, as described heretofore, signal light 20 when illuminated gives a green signal to the train on the track at the left side of the signal device and gives a red signal to the train on the right side. Signal light 5 when illuminated gives a green light to the train on the right side of the signal device and a red light to the train on the left side of the device. Of course, only one signal is operating at one time so that there is no confusion to the train operators.

In order to facilitate the observation of the signals by the train operators an outwardly projecting vertical web 113 is located on the front of the casing 101 between the two vertical sets of lights 108, 110 and 109 and 111. It will be observed that the aforesaid structure provides a compact, simple and reliable signal device.

My invention is equally applicable to a

5 railroad system in which the tracks cross each other at some angle, say 90 degrees, as illustrated in Fig. 5. The main line in this illustration is designated by the letter M' and the local line by the letter L'.

When an express train X-T comes within the live section L of track limited by insulating blocks 16 and 17 which are interposed in the same rail, my automatic power 10 cut-off system S is caused to come into operation and automatically cut off the power in the third rail T' feeding the local train L-T. The elements constituting my automatic power cut-off system are the same as those 15 described hereinbefore and a discussion thereof will not be repeated. It is sufficient to say that the electro-magnet circuit M is connected to the main line M' whereas the armature circuit K is connected to the local 20 track L'. Thus when the express train X-T gets into the live section defined by the insulating blocks 16 and 17 the electro-magnet circuit is completed and the electro-magnet energized so that the armature is attracted 25 thereto. This breaks the circuit between a portion of the third rail 52 and another portion of the third rail 53 so that the third rail T' between insulating blocks 18 and 19 is rendered dead. The local train therefore has 30 no power and cannot proceed across the main line track. Consequently it is perfectly safe for the express train, seeing a green signal emitted by light 5 in signal device C to proceed at its usual speed. Light 5 also lights 35 a red light warning the operator of the local train that he cannot go any farther and should apply his air brakes.

It will be apparent from the aforesaid description that my system can be applied with 40 equal success to a cross railroad system.

The signal device C consists of a casing 120 of rectangular cross-section which is mounted upon a pedestal 121 as may be clearly seen in Fig. 8. Since the construction of 45 the pedestal 121 is similar to pedestal 102 with its auxiliaries, the description will not be repeated for pedestal 121. Signal light 5 is mounted on a horizontal partition 123 and is adapted, when illuminated, to cause the 50 emission of green light from the green window 124 and of red light from the red window 125. The green signal from window 124 facing the main line M' is intended for the express train whereas the red signal from window 125 facing the local line L' is for the local train. In the lower part of the signal device light 20 is mounted on base 127 which has a red window 126 and a green window 127 associated therewith. When 55 light 20 is illuminated window 126 emits a red light for the express train on the main line and window 127 emits a green light for the local train on the local line.

In Fig. 9 I have depicted, in a somewhat fragmentary manner, my improved auxiliary

device adapted to be incorporated in the air brake system of a train so that if the operator of a train fails to apply the air brakes of the train upon coming into a danger or dead section, the auxiliary device will automatically apply the air brakes. In the auxiliary device conductors 150 and 151 are connected in the power circuit of the train which is fed with electrical energy from the third rail or equivalent system. Conductor 150 is 70 connected to an electro-magnet 153 through a resistance 152 and conductor 151 is connected directly to the electro-magnet. Operatively associated with the electro-magnet is an armature 154 which is mounted on pivot 156 75 and which is herein shown as attracted to the core 171 of the electro-magnet against the tension of spring 155. At the other side of the pivot 156 a hook 157 is provided which engages the end of a crank 160. This crank is 80 rotatable about the pivot 162 and has a tension spring 161 attached to the other end.

A link 163 is secured to an arm 165 which actuates a valve 166 in a by-pass air line 167. This by-pass line is connected to pipe 168 85 leading from the compressed air tank (not shown) and to a pipe 170 leading to the air brakes (not shown). In the pipe line 168-170 the usual manual air brake control mechanism 169 is incorporated in the custom- 90 ar manner.

When a train is equipped with my auxiliary device proceeds into a danger or dead zone of track, the auxiliary device automatically causes the application of the air brakes 100 to stop the train. In a dead section, as pointed out heretofore, the third rail or equivalent electrical conductor is de-energized so that no electrical energy flows to the train. As soon as the power circuit on the 105 train is de-energized the electro-magnet 153 becomes de-energized and cannot hold the armature to the core 171 against the tension spring 155. This causes armature 154 to pivot about 156 and move hook 157 downwardly, thus permitting the release of crank 160. Spring 161 pulls crank 160 against stop 164, and, thus, causes movement of link 163 and arm 165. By turning arm 165 the air valve 166 is actuated to open the valve and 110 permit air to flow from the air tank line 168 through by-pass 167 to pipe 170 which leads to the air brakes. Air thus passing through pipe 170 to the air brakes causes the application 115 of them to stop the train. In this manner the train is automatically stopped as soon as it has entered into a dead section of track which has been de-energized by the operation of my automatic power cut-off system. It will be observed, therefore, that 120 even if the operator of a train fails to apply the brakes of the train for any reason at all, my auxiliary device will automatically apply the brakes and will cause stoppage of the train, thus insuring the safety of the passen- 125 130

gers and positively preventing any collisions. After the train has come to a stop and before it begins to proceed again the operator of the train re-sets the auxiliary air valve 166 and mechanism associated with the electro-magnet 153 so that it is in condition for operation again. It is obvious, of course, that well-known mechanism may be used for resetting the air valve.

10. It will be noted that my invention provides an electrical railroad with an automatic safety system which insures absolute safety to the trains operating on the railroad and which eliminates the possibility of collisions 15 between trains running on the same track or on conflicting tracks. The incorporation of my system in underground railways, such as the subways of New York, will make it possible to prevent accidents resultant from collisions and to permit the operations of trains 20 by relatively inexperienced operators.

What I claim is:—

1. In an electric railroad system the combination which comprises a live section of 25 railroad track, a second section of track conflicting with said live section and capable of being rendered dead and an electro-magnet circuit connected in shunt with the power circuit of said live section of track, an armature circuit connected in series with the power circuit of said second section of track, said 30 electro-magnet circuit and said armature circuit being associated with each other in such a manner that when a train is located in the 35 first-named section of track the electric power is cut off in the power circuit of said second-named track, and a signal system electrically connected with said electro-magnet circuit and said armature circuit in such a manner 40 as to operate and signal to an anterior train in the live section to proceed and to a posterior train in the second section to stop.

2. In an electric railroad system the combination which comprises a live section of 45 railroad track, a second section of track conflicting with said live section and capable of being rendered dead and an electro-magnet circuit connected in shunt with the power circuit of said live section of track, including 50 an electro-magnet, a resistance element connected in series with said electro-magnet circuit to reduce the voltage, an armature circuit connected in series with the power circuit of said second section of track, said electro-magnet circuit and said armature circuit being 55 associated with each other in such a manner that when a train is located in the first-named section of track the electric power is cut off in the power circuit of said second- 60 named track, a signal connected to said electro-magnet so as to emit a green light to an anterior train in the live section of track and a red light to a posterior train in the dead section of track only when a train is located 65 in the live section of track, and a signal con-

nected to said armature circuit so as to emit a red light to the live section of track and a green light to the second section when the power circuit of the second section is energized.

In testimony whereof I have hereunto set my hand.

RICHARD CRETER.
